(57) **CLAIM**

The ornamental design for an air gun magazine, as shown and described.

DESCRIPTION

FIG. 1 is a front perspective view of illustrating my new design for an air gun magazine;

FIG. 2 is a rear perspective view thereof;

FIG. 3 is a front view thereof;

FIG. 4 is a rear view thereof;

FIG. 5 is a left side view thereof;

FIG. 6 is a right-side view thereof;

FIG. 7 is a top view thereof; and,

FIG. 8 is a bottom view thereof.

The broken line in the drawings depicts unclaimed portion of the air gun magazine only and forms no part of the claimed design.
